DESIGN FOR A BOTTLE

Garland D. Runnels, Seattle, Wash.

Application June 27, 1938, Serial No. 78,097

Term of patent 14 years

To all whom it may concern:

Be it known that I, Garland D. Runnels, a citizen of the United States, residing at Seattle, in the county of King and State of Washington, have invented a new, original, and ornamental Design for Bottles, of which the following is a specification, reference being had to the accompanying drawing, forming part thereof.

Figure 3 is a front view in elevation,
showing my new design.

I claim:

The ornamental design for a bottle, substantially as shown.

GARLAND D. RUNNELS.
